[57] **CLAIM**

The ornamental design for an H-connector for a toy construction system, as shown and described.

DESCRIPTION

FIG. 1 is a top, front perspective view of the H-connector, showing our new design;

FIG. 2 is a bottom, front perspective view thereof;

FIG. 3 is a top plan view thereof;

FIG. 4 is a bottom plan view thereof;

FIG. 5 is a side view thereof, the side opposite being identical;

FIG. 6 is an end view thereof, the side opposite being identical; and,

FIG. 7 is a perspective view of a building block utilizing four H-connectors of a toy construction system, the broken line showing of the block and three connectors is for illustrative purposes only and forms no part of the claimed design.
